United States Patent Office

Des. 210,255

Patented Feb. 20, 1968

210,255

CINEMATOGRAPHIC CAMERA

Bernhard Jablonski, Musberg, Germany, assignor to
Robert Bosch Elektronik und Photokino GmbH,
Stuttgart-Unterfuerkheim, Germany

Filed June 13, 1966, Ser. No. 2,664

Term of patent 7 years

(Cl. D61—1)

FIG. 1

FIG. 5

FIG. 2

FIG. 6

FIG. 3

FIG. 4

FIG. 1 is a side elevational view of a cinematographic camera, showing my new design;

FIG. 2 is an opposite side elevational view;

FIG. 3 is front elevational view;

FIG. 4 is a rear elevational view;

FIG. 5 is a top plan view; and

FIG. 6 is a bottom plan view thereof.

The essential features of the design reside in the portions shown in full lines on the drawings.

The drawing figures are shaded to indicate contrast in appearance.

I claim:

The ornamental design for a cinematographic camera, substantially as shown and described.
